UNITED STATES PATENT OFFICE.

THOMAS L. STURTEVANT, OF QUINCY, AND THOMAS JOSEPH STURTEVANT, OF WELLESLEY, MASSACHUSETTS, ASSIGNEES TO STURTEVANT MILL COMPANY, A CORPORATION OF MAINE.

SCREENING OR SEPARATING MACHINE.

1,229,809.

Specification of Letters Patent. Patented June 12, 1917.

Application filed June 10, 1916. Serial No. 102,830.

To all whom it may concern:

Be it known that we, THOMAS L. STURTEVANT and THOMAS J. STURTEVANT, citizens of the United States, residing, respectively, at Quincy and Wellesley, in the county of Norfolk and State of Massachusetts, have invented or discovered certain new and useful Improvements in Screening or Separating Machines, of which the following is a specification, reference being had therein to the accompanying drawings.

This invention relates to certain improvements in the screens or separators covered by the Sturtevant Patents No. 1,035,262, Aug. 13, 1912; No. 1,114,064, Oct. 20, 1914, and No. 1,116,512, Nov. 10, 1914; the present invention having for its object to increase the efficiency and convenience of the class of separators to which the said patents relate, 20 as will hereinafter be fully set forth.

In the accompanying drawings Figure 1 is a front view of the improved separator. Fig. 2 is a broken outside view thereof. Fig. 3 is a detail perspective view showing 25 a preferred construction for removably attaching the sections of the screen box or casing together. Fig. 4 illustrates a removable half head for the feed box in elevation and in plan and edge views.

Referring to the drawings 12 denotes a screen box or casing supported in an inclined position on a suitable frame-work 13, suitable means being provided whereby the inclination of the said box or casing may be varied as is sometimes desirable in working on different kinds of materials. In order to increase the capacity of the separator the box or casing is preferably made of greater height or length than heretofore, and for convenience in transportation is preferably made in two sections detachably secured together by means of angle-bars 14 riveted or otherwise permanently secured to the adjacent ends of the sections, the contiguous 40 outwardly-projecting flange parts of the said angle-bars being joined by bolts 15 which may be removed when the sections are to be taken apart. Instead of these angle-bars 14 the screen box sections may be provided with integral outwardly-projecting flanges 14^a detachably secured together by removable bolts 15.

Also in order to increase the efficiency of the separator the feed box 16 is made somewhat longer than the width of the casing 12,

and projects laterally beyond the said casing at the supply end of said feed box, so that the material supplied to the said feed box through the hopper opening 16^a and fed to the screens will cover the entire width of the upper ends of the screens which was not the case in the former separators, in that the stream of material issuing from the feed box was not quite as wide as the screens. The rotary conveyer 17 in the feed box, and 60 which feeds the material in said box to the screens, is also made longer than the width of the screens so that a stream of material fully as wide as the screens will be supplied thereto.

The rotary screw conveyer 17 is carried by a shaft 18 provided with a driving pulley 19, the said shaft having at its end opposite said driving pulley a second and removably mounted pulley 20 from which power is 70 taken for rotating the shafts 21 carrying the cams 22 which lift the gravity-operated hammers 23 acting on the posts 24 which jar the screens, within the box or casing 12, by percussive action. For convenience in placing 75 the conveyer shaft 18 in working position or for removing it therefrom, the feed box is provided at one end with a removable or sliding portion 25 which, when the cover of the said feed box has been removed or 80 turned back on hinges, may be taken out, thus enabling the conveyer shaft, when the pulley 20 has been removed, to be inserted in place from the top of the box, and then by a short endwise movement be brought 85 fully into working position. If desired, however, the feed box 16 may be provided at each end with a removable or sliding portion 25, and in such case said shaft, with its attached conveyer, may be placed into 90 or taken out of its working position, from the top of the box, without the necessity of removing the pulley 20.

In order to provide for a variable percussive action of the hammers 23 each of said 100 hammers is preferably formed with a receptacle or pocket 26 adapted to receive molten lead, in any desired quantity, to add to the weight of the hammers and thus increase their percussive action on the screen-jarring posts 24.

In separators of this kind the speed of descent of the material increases from the tops to the bottoms of the inclined screens, and if these screens extended uninterruptedly from 110

the tops to the bottoms of long screen boxes the speed of the descending material in the lower portions of the screen boxes would be so great that comparatively little of the fine material would pass through the lower parts of the screens. To avoid this objection the fine mesh screens of the present improved separators are made in two parts so arranged that the material passing over an upper screen or screen section will be caused to pause in its descent before being delivered to a lower screen or screen section.

The material passing from the feed box 16 is first delivered onto a receiving plate 27, preferably provided with a retarder 28, the material passing from the said receiving plate 27 to a scalper screen the tailings of which are delivered to a tailings chute 30 which carries them out of the screen box. The material passing through the scalper screen 29 is received on the upper fine screen section or screen 31, and the material passing over the said screen section or screen 31 is delivered to a shelf 32 above which is a depending retarding plate 33 which will serve to check the downward travel of the material delivered from the screen 31 and cause it to drop onto the said shelf 32. From the shelf 32 the material is delivered to the lower fine screen section 34, and the tailings from the said screen section 34 are delivered outside of the screen box 12. The fine material passing through the screens 31 and 34 falls to the bottom of the screen box and slides down the same to a proper delivery opening. The imperforate tailings chute 30, in the lower screen box section or unit, prevents any relatively coarse material from falling on the lower fine screen 34 below it, said screen 34 receiving material only from the screen 31.

From the foregoing it will be understood that the travel of the material passing down the fine screens will be interrupted at the lower end of the upper screen or screen section before being delivered to the lower screen or screen section, and thus the travel of the material over the lower screen section will not be more rapid than its travel over the upper screen section.

The percussively jarred fine screens 31 and 34 are supported by springs 35 beneath which are disposed stops 36 which will limit the downward movements of the screens under the jarring action of the posts 24 percussively acted on by the hammers 23.

For convenience in looking or reaching into the chamber of the screen box 12 said screen box is preferably provided at one or both sides with observation holes or hand holes 37 provided, in practice, with removable covers which may be taken off when desired. The lower observation hole is adjacent the receiving shelf 32 with which the retarder plate 33 cooperates, so that by look-

ing through said hole the operation of the retarder may be observed, and as the said retarder plate is of thin metal it may be bent slightly forward or backward (or up or down) to vary its working.

Each section of the screen box is provided with a hinged cover 38 supporting jarring mechanism or devices, and each section of the screen box contains its own screen or screens; so that the present improved separator may be said to contain a plurality of complete screen units adapted to be secured together or removed from each other, in that each unit has its own screen or screens and jarring devices. Thus, for convenience in transportation, the complete screen section units may be packed separately, and may be readily secured together in setting up the separator for use.

The frame-work 13, by which the screen box or casing is adjustably supported in an inclined position, may, for affording adjustment, comprise horizontal bars having a jointed connection, as at 13^a, with the lower end of said box or casing, upright bars jointed at 13^b to said horizontal bars, and adjustable connections between flanges 39 on the screen box or casing and the upper parts of said upright bars, the upper parts of said upright bars and the said flanges having holes 40 for the reception of removable pins or bolts 41 which may be placed in different holes in effecting an adjustment of said screen box or casing in varying its angle of inclination. Of course a proper looseness between the flanges 39 and the said upright bars will be provided to accommodate the varying positions of the screen box.

Having thus described our invention we claim and desire to secure by Letters Patent:

1. In a separator, a screen box or casing consisting of a plurality of sections detachably secured together, each section being provided with screens which are mounted for being percussively jarred, and each section being also provided with jarring mechanism for said screens, combined with a feed box which is a permanent part of the upper section or unit, a rotary conveyer mounted in said feed box, and a shaft by which said conveyer is carried and from which shaft the operating shafts, forming parts of the jarring mechanisms of both of said sections or units, are driven.

2. In a separator, the combination with an inclined screen box or casing, of separated screens in the upper and lower portions of said casing, and retarding means between said screens for checking the descent of the material from the upper screen before the same is delivered to the lower screen, said retarding means comprising a shelf receiving material discharged from the upper screen and a depending retard-

ing plate for checking the downward travel of the material and diverting it to said shelf on which it is momentarily detained.

3. In a separator, the combination with 5 an inclined screen box or casing and screens within the same, of a feed box arranged at the upper end of said casing and of a greater length than the width of said casing, said feed box extending laterally beyond 10 the casing, and a rotary conveyer in said feed box which is also of greater length than the width of said screens and which also extends laterally beyond the casing at the end thereof at which the material enters.

4. In a separator, the combination with an inclined screen box or casing and screens within the same, of a feed box arranged at the upper end of said casing and provided 20 with a hopper opening near one end, the said feed box extending laterally beyond said casing at its end having the hopper opening, and a rotary conveyer within said feed box and of greater length than the width 25 of said casing, the end of said conveyer, at the entering end of the material, extending laterally beyond the casing and being beneath said hopper opening.

5. In a separator, the combination with 30 an inclined screen box or casing, of separated screens in the upper and lower portions of said casing, and retarding means between said screens for checking the descent of the material from the upper screen before the same is delivered to the lower screen, said retarding means comprising a

shelf receiving material discharged from the upper screen and a depending retarding plate for checking the downward travel of the material and diverting it to said shelf, 40 said box or casing having in its side an observation hole adjacent said shelf so that the working of said retarding means may be observed from the outside of said box or casing

45 6. In a separator, an inclined screen box or casing consisting of two sections or units detachably secured together, the upper screen box section or unit being provided with a coarse or scalper screen and a fine 50 screen below it, and the lower screen box section or unit being provided with a chute, to which the tailings from said coarse or scalper screen are delivered, and with a fine 55 screen below the tailings chute and to which last-named fine screen material is delivered from said first-named fine screen.

7. In a separator, an inclined inclosed screen box or casing consisting of a plurality of sections or units detachably secured together, each section or unit being provided with its own screen or screens which are mounted for being percussively jarred, and each section or unit being provided with its own jarring mechanism, combined with a 60 prime mover from which the said jarring mechanism of the said sections or units may be operated.

In testimony whereof we affix our signatures.

THOMAS L. STURTEVANT.

THOMAS JOSEPH STURTEVANT.
